UNITED STATES PATENT OFFICE.

ENOCH GEORGE, JR., OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

CAR-COUPLING MECHANISM.

Application filed October 13, 1925. Serial No. 62,265.

The invention relates to car coupling mechanism, commonly known as transition couplings, employed for the purpose of connecting a car equipped with an automatic coupler of the vertical plane type to a car equipped with a drawhook or the like.

The principal object of the invention is to provide a device of this character which is strong and of simple construction and which may be easily and quickly manipulated.

A principal feature of the invention consists in providing a loop member which extends transversely of the coupler head and is journalled at its opposite ends on the upper side of said head, a link device which is movably attached to the loop member being provided for cooperation with a drawhook.

A further feature of the invention consists in providing a loop member which is journalled at its opposite ends upon the upper side of the coupler head, and in combining therewith a link device for cooperating with the drawhook, the loop member being formed with a curved intermediate portion which normally extends forwardly beyond the central portion of the forward face of the coupler head.

Another feature of the invention consists in providing the coupler head with upwardly extending lugs forming journal bearings for the transversely extending loop member, the said lugs being disposed upon opposite sides of the longitudinal axis of the coupler and one of them forming a segmental journal bearing for the loop member.

Other features of the invention relating to particular relations of parts and advantageous details of construction will hereinafter appear.

In the drawings illustrating a preferred embodiment of the invention, the scope whereof is pointed out in the claims,

Figure 1 is a plan view of a coupler, transition gear and drawhook, the parts being connected and in pulling relation.

Figure 2 is a side elevational view of the mechanism.

Figure 3 is a view partly in section and partly in front elevation, showing the relation of the transition gear to the coupler.

Figure 4 is a detail side elevational view, looking toward the guard arm side of the coupler head, of a portion of the mechanism.

In the construction illustrated in the drawings, 1 is a coupler whose stem is attached to the car by means of suitable draft rigging appliances in any well known or desired manner. Rotatably mounted upon the head 2 of the coupler is a knuckle 3, the pivotal connections of these parts being made by the usual knuckle pin 4. Suitable locking mechanism 26 cooperates with the knuckle to restrain outward or uncoupling rotation of the latter. These features of construction are commonly known and require no extended description.

Mounted upon the upper side of the coupler head 2 is a loop member 5 which is adapted to be connected to a drawhook 6 through the intervention of a link device preferably comprising an eye-bar member 7 and a link 8. The openings 9 in the member 7 for respectively receiving the loop member 5 and link 8 are, as shown, flared in order to prevent these connected parts from binding on each other when cars are passing around a curve. The curved intermediate portion 10 of the loop member is offset with respect to the journal ends thereof so as to be positioned in advance of the central portion of the forward face of the coupler head 2 when the loop member 5 is in operative position.

Cast integral with the coupler head are upwardly projecting lugs, 11 and 12 respectively, which form journal bearings for the corresponding ends of the loop member 5. These lugs are positioned on opposite sides of the longitudinal axis of the coupler, one of them preferably being closely adjacent the knuckle pin 4 and the other being advantageously located substantially at the outer end of the guard arm portion of the coupler head. The journal bearing constituted by the lug 11 is preferably in the form of an eye so as completely to encircle the adjacent journal end 13 of the loop member, while the bearing formed by the lug 12 for cooperating with the opposite journal end 14 of the loop member is segmental. As a convenient means for retaining the loop member 5 in journalled relation to the lugs 11 and 12 of the coupler head it is preferred to employ a pin 15 which is mounted on the coupler head immediately to the rear of the journal bearing lug 12 and whose upper end overlaps the neighboring end 14 of the loop

member. The pin 15 may be retained in assembled relation by means of a cotter 16. The bearing faces of the lugs 11 and 12 which engage the ends of the loop member 5 when the latter is in operative position are curved to conform to the cooperating portions of the loop member; and to afford clearance to enable the loop member 5 to be assembled and disassembled, the rear portion 10 of the eye of the lug 11 is flared, as indicated at 17. As a means for preventing lateral shifting of the loop member 5 with respect to the coupler head, the ends of said loop member are preferably formed with shoulders or lugs 18 which overlap neighboring portions of the correspondingly adjacent lugs 11 and 12 in which the loop member 5 is journalled.

It will be understood that when the automatic coupler is to be coupled with a similar coupler on an adjacent car the loop member 5 will be rotated rearwardly so as to be out of the way. In this position of the loop member the bar 7 and the drawhook link 8 hang down over the guard arm of the coupler head 2.

In order to insure that the knuckle 3 shall remain in open position when the transition gear is in use so as to avoid interference with the latter, it is preferred to mount a coil spring 19 on the lower end of the knuckle pin 4, one end of said spring extending into a perforated lug 20 at the lower end of the pulling lugs of the knuckle 3 and the other end similarly cooperating with a perforated lug 21 projecting downwardly from the underside of the coupler head.

The means illustrated in the drawings for operating the coupler locking mechanism 26 are of a well known character and comprise a bell crank lever 22 which is pivotally attached by a pin 23 to lugs 24 formed on the underside of the coupler head. One arm of the lever 22 is provided with the customary eye 25 for permitting attachment of a pull rod such as is usually employed for operating an unlocking lever of this character.

I claim:

1. Car coupling mechanism comprising a coupler head, a knuckle rotatably mounted on said head, and a lock for said knuckle, in combination with means adapted to connect said coupler to a drawhook, said means including a pivoted member extending trans-

versely of the coupler head and journalled on the upper side of the latter, and a link device movably connected to said transversely extending member and adapted to cooperate with a drawhook, said head being provided on opposite sides of the longitudinal axis of the coupler with lugs respectively forming journal bearings for the ends of said transversely extending member, and said transversely extending member being provided at its ends with means extending at an angle to its pivotal axis for engaging said lugs to limit shifting of said transversely extending member laterally of the coupler, and means associated with one of said lugs for detachably maintaining the transversely extending member in assembled position.

2. Car coupling mechanism comprising a coupler head, a knuckle rotatably mounted on said head, and a lock for said knuckle, in combination with means adapted to connect said coupler to a drawhook, said means including a loop member journalled at its opposite ends on the upper side of the coupler head and having a curved intermediate portion normally extending forwardly, said head being provided on opposite sides of its longitudinal axis with lugs forming journal bearings for said loop member, one of said journal bearings being open on one side, means for retaining said loop member in assembled relation to said lugs, and means movably connected to said loop member for connecting the latter to a drawhook.

3. Car coupling mechanism comprising a coupler head, a knuckle rotatably mounted on said head, and a lock for said knuckle, in combination with means adapted to connect said coupler to a drawhook, said means including a member extending transversely of the coupler head and journalled on the upper side of the latter, and a link device movably connected to said transversely extending member and adapted to cooperate with a drawhook, said head being provided on opposite sides of the longitudinal axis of the coupler with lugs respectively forming journal bearings for the ends of said transversely extending member, and means mounted on the head adjacent one of said lugs for detachably maintaining the transversely extending member in assembled position.

In testimony whereof I affix my signature.
ENOCH GEORGE, JR.
